Attorney

Patented Apr. 3, 1923.

UNITED STATES PATENT OFFICE.

CHARLES W. HOLBROOK, OF PROVIDENCE, RHODE ISLAND.

BUFFER FOR PICKERS.

Application filed May 6, 1922. Serial No. 558,857.

To all whom it may concern:

Be it known that I, CHARLES W. HOLBROOK, a citizen of the United States, residing at Providence, in the county of Providence and State of Rhode Island, have invented certain new and useful Improvements in Buffers for Pickers, of which the following is a specification.

My invention relates to buffers or bunter checks for loom pickers and particularly for pickers of the reversible type.

The essential objects of my invention are durability; to afford a requisite cushioning effect while avoiding the recoil incident to the use of buffers having rubber as a constituent part or in the form of loops or rings; to afford such toughness as to avoid tearing or deformation, and to prevent fracture, and to prevent torque of the picker and to avoid strains.

To the above ends essentially my invention consists in such parts and in such combinations of parts as fall within the scope of the appended claims.

25 In the accompanying drawings which form a part of this specification,

Figure 1 is a fragmentary plan view of the portions of the loom adjacent the picker, in which my buffer is shown in plan,

30 Figure 2, a perspective view of the buffer, and

Figure 3, a section of the latter on line 3—3 of Figure 2.

Like reference characters indicate like 35 parts throughout the views.

In the drawings 4 is the shuttle box, 5 the guide plate, 6 the picker rod, 7 the picker stick, and 8 the frame support of one end of a loom lay. A shuttle 10 in the 40 shuttle box is shown contacting with an operating face of a picker 12 slidable on its rod 6 and extending through the guide slot 13 of the guide plate. The picker comprises as usual the broad body 15 and retracted neck 16 and head 17 whereby are formed lateral recesses or cut away portions 18. It is in conjunction with these familiar parts that my buffer 20 will be described.

This member is oblong comprising a 50 broad head portion 21 which is tapering forwardly, as at 22, to merge in a forward neck portion 23.

The buffer is composed of a series of superposed strips or layers 25 of raw hide 55 so disposed that their edges constitute the

front and back operating faces 26 and 27 respectively. This edgewise arrangement of the layers is essential. The layers, with cement placed therebetween, are subjected to hydraulic pressure. Near its end the 60 neck portion 23 of the buffer is provided with a horizontal hole 29 for slidably receiving the rod 6, and with vertical holes 30 to receive rivets 31. The head portion 21 also has a vertical hole 32 to receive a rivet 65 33. The buffer extends through the slot 13 of the guide plate intermediate the picker and loom portion 8.

It will be observed that the contact of the picker face is against the edges of the layers 70 25 upon the face 26, and that the face 27, adapted to abut the loom portion 8, has the edges of the layers presented to the latter.

It will be observed that the head and the neck of the buffer are adapted to receive the 75 impact of the picker head and the picker body respectively, and thus distortion of the picker is prevented. In operation the shuttle first contacts with the picker and then the latter is moved against the buffer 80 and by reason of the face contact at opposite sides of the picker both ends thereof are cushioned and the picker is kept square on its spindle, thus preventing torque. 85

I claim:—

1. A buffer for looms comprising a broad head portion adapted to receive the impact of a picker head and a narrow portion to receive the impact of the picker body.

2. A buffer for looms comprising a broad head portion to receive the impact of a picker head and a narrow neck portion to receive the impact of the picker body, said head and neck portions consisting of superposed layers of tough material disposed 90 with their edges constituting the operating face of the buffer.

3. A buffer for looms comprising a broad head portion adapted to receive the impact of a picker head and a narrow neck portion 100 to receive the impact of a picker body, the said head and neck portions formed of superposed layers of tough material disposed with their edges to constitute the impact face of the buffer, and means holding said 105 layers in close contactual engagement with each other throughout their length.

In testimony whereof I have affixed my signature.

CHARLES W. HOLBROOK.
